UNITED STATES PATENT OFFICE.

WILLIAM S. OSBORNE AND ELWIN C. BRYANT, OF ST. LOUIS, MISSOURI.

PNEUMATIC GRADER.

SPECIFICATION forming part of Letters Patent No. 710,603, dated October 7, 1902.

Application filed December 17, 1900. Serial No. 40,176. (No model.)

To all whom it may concern:

Be it known that we, WILLIAM S. OSBORNE and ELWIN C. BRYANT, citizens of the United States, residing at the city of St. Louis, in the State of Missouri, have invented a certain new and useful Improvement in Pneumatic Graders, of which the following is a full, clear, and exact description, such as will enable others skilled in the art to which it appertains to make and use the same, reference being had to the accompanying drawings, forming part of this specification, in which—

Figure 1 is an elevational view, partly in section, the section being taken on line 1 1, Fig. 3, of our improved pneumatic grader. Fig. 2 is a vertical sectional view on line 2 2, Fig. 3. Fig. 3 is a horizontal sectional view on line 3 3, Fig. 1; and Fig. 4 is a view illustrating a system of pulverizing and grading material, showing our improved grader in said system.

This invention relates to a new and useful improvement in pneumatic graders designed especially for use in connection with systems for pulverizing and grading material, such as shown in an application filed by us contemporaneously herewith on December 17, 1900, Serial No. 40,177, and designated "Case A," the object being to separate the particles of pulverized material from air for the purpose of collecting the same either in the form of finished product or as tailings to be returned to the grinding or pulverizing machine.

One of the objects of our present invention is to provide a simple and cheap construction for effecting the separation or grading of pulverized material, utilizing rarefied air for the purpose of effecting such separation, the heavier particles falling to the bottom of the apparatus while the lighter particles are carried off. We propose using an exhaust-fan in connection with our improved grader for rarefying the air therein, thus forming a suction on the grinding-machine sufficient to take away and elevate the pulverized material into our improved grader as fast as it is ground and also drawing off the lighter particles of dust from the grader, the heavier particles being returned to the grinding-machine or collected as a finished product, as desired.

With these objects in view our invention

consists in the construction, arrangement, and combination of the several parts, all as will hereinafter be described and afterward 55 pointed out in the claims.

Referring to Fig. 4, wherein is illustrated a system for pulverizing and grading material, A indicates a machine for reducing material to a finely-divided state, the material to be reduced being fed into said machine through a closed hopper containing a feeding apparatus a. This reducing-machine may be of any desirable construction, and we have not, therefore, shown the details of the 65 same in the drawings.

B indicates a spout leading from the top of the machine, into which the reduced material from the machine is received.

b is a valve in the spout B.

The spout B leads into what we have designated as "grader" C, the details of which are shown in Figs. 1 to 3. This grader preferably consists of an octagonal casing having a conical lower portion discharging into a 75 spout D, which spout connects with the feed end of the machine and is provided with a valve d. The top of the grader is closed by a suitable cover.

E indicates a deflector secured to the grader 80 in advance of the inlet-opening, said deflector being attached at one side and to the top of the grader, an opening or space being provided at the opposite side and bottom of said deflector for the passage of the dust-laden 85 air.

In speaking of the dust-laden air we wish to be understood as meaning the air coming from the grinding-machine, which serves as a vehicle to carry the particles of reduced material in suspension. When this dust-laden air is introduced into the grader C, it strikes the deflector E and is caused to take other than a straight path, being directed downwardly and to one side, so that the heavier 90 particles will fall and the lighter particles will be carried by the air to and through the escape-opening. By reason of the polygonal shape of the casing eddies are formed, which give to the dust-laden air a whirling motion, 100 which enables the heavy particles to be more readily affected by the greater vacuum in the bottom of the casing. Where two grinding-machines discharge into a single grader, we

prefer to employ a pipe B' and a deflector E', which operate in substantially the same way as above described. However, in this description we will assume that the pipe B' is a blind pipe, having a cap provided at its end.

5 F indicates a discharge-pipe leading from the head of the grader opposite the inlet-pipe B, said pipe F being of larger diameter than the inlet-pipe B and connecting with the eye 10 of a fan G. A suitable valve f is arranged in the pipe F.

H indicates a pipe leading from the fan G into the head of a separator I.

In using the term "grader" in connection 15 with this construction we do so primarily to distinguish this part of our apparatus from the separator. The purpose of this so-called "grader" is to form a strong suction on the mill, so as to relieve it of the fine and coarse 20 dust before said dust reaches the speed of the beaters in the mill, and when this dust is drawn into the grader to initially grade the pulverulent material, returning the large particles, called "tailings," back to the grinding- 25 machine to be reduced and permitting the particles of sufficient fineness to pass on beyond the grader. This greatly increases the capacity of the mill. In other words, this so-called "grader" serves as a screen in that 30 by regulating the valves in the spout of the exhaust-fan it is possible to cause material of varying degrees of fineness to be passed therethrough, say, up to a certain mesh, those particles of material exceeding in size the desired 35 mesh being returned to the machine for regrinding or to a suitable receptacle as finished product. It will be observed that the grinding-machine, operating in a closed system, will thoroughly reduce the material. The 40 vacuum in spout B can be regulated by the valve b. The dust-laden air entering the grader will be deflected laterally and downwardly, the tortuous passage it is compelled to follow forming eddies, causing the dust-laden air to whirl, resulting in the precipitation 45 of heavier particles of material into the pipe D, which connects with the feed end of the pulverizer. The outlet-pipe F being of larger area than the inlet-pipe and connected 50 with the eye of an exhaust-fan will have a constant tendency to draw and exhaust all the air and its carried particles of material through the grader. The amount of air admitted to the grader is controlled by the valves b and d, 55 the available area through which said air is drawn into the fan being controlled by the valve f.

It is well known that particles of material held in suspension in air rely upon the air 60 resistance for their buoyancy; that if said particles of material were placed in a vacuum-chamber, wherein the air would offer no resistance to the action of gravity, said particles of material would be practically dead, so 65 far as their floating capacity is concerned. We take advantage of this natural law in effecting the grading action in the chamber

C by exhausting the air from said chamber and creating a partial vacuum therein, the greater vacuum being at the bottom of the 70 grader, where no air is admitted, so as to take away from the particles of material the sustaining properties of the air, rendering them more susceptible to the action of gravity. Being introduced into a chamber from which 75 the air is being constantly exhausted and wherein there exists a partial vacuum, and being compelled to take a tortuous passage at the time of introduction into said chamber, the particles of material will immediately become more susceptible to the action 80 of gravity when they reach the grading-chamber, and the heavier particles will fall and the lighter particles will be drawn into the pipe F to the exhaust-fan. By regulating the 85 valve d the fineness of the particles entering the pipe F can be controlled. If said valve is closed or nearly closed, it follows that there is no upward circulation of air through the pipe D. Therefore the heavier particles are 90 not resisted in their descent, and a more finely-divided product will thus pass through the pipe F. If, on the other hand, the valve d is open to permit an upward circulation of air therethrough, the particles of material meeting with this resistance are held in suspension 95 by the air passing upwardly through the pipe D, and consequently the material passing through pipe F is of a coarser quality. In order to get a fine grade of material, the valve d is 100 kept closed, or nearly so, allowing only a sufficient opening for the discharge of the tailings. The regulation of valve b is such that the opening controlled thereby is about sufficient to take care of the capacity of the grinding-machine without admitting an excess 105 quantity of air at this point; but of course it will be understood that the valve b, being open full, will affect the degree of fineness of the particles of material passing through the 110 pipe F. However, it is not intended to use the valve b for the purpose of accomplishing this, said valve being designed primarily to control the exit-opening from the grinding-machine, and thus goes more to accommodating 115 the capacity of said machine than to controlling the quality of ground material passing beyond the grader. The valve f is adjustable to regulate the discharge-opening from the grader according to the capacity of 120 the fan, and while the opening controlled by this valve will affect the quality of material passing therethrough said valve is not intended to be used for this purpose, we preferring 125 to rely rather on the valve d, which is not only more accessible, but depending upon conditions can be manipulated as occasion requires—as, for instance, an excess of heavy particles falling into the pipe D would require the valve d to be opened to a greater 130 extent to permit of a proper discharge thereof, while a scarcity of material in pipe D would require that the valve d be closed, or nearly so, to prevent the outside air rushing in. The

accessibility of valve *d* and its ease of manipulation is of advantage in the event of an irregular feed of material into the grinding-machine. If the material to be ground is 5 not regularly fed and there is no regulation of valve *d*, it follows that a variation in the quality of the product will result which is undesirable.

The pipe *H*, being the discharge-pipe from 10 the exhaust suction-fan *G*, leads into a separator *I*, the details of construction of which are not shown in this application, they forming the subject-matter of a separate application filed contemporaneously herewith on December 17, 1900, Serial No. 40,178, and designated "Case C." However, we will state that the particles of dust are collected in the separator, being deposited in a spout *J*, controlled by a valve *j*, the air containing finely- 15 divided material, which is practically inseparable therefrom, passing through a pipe *K* into an auxiliary separator *N*, which is provided with a down-spout *O*, carrying such particles of dust as may be collected in this 20 auxiliary separator back to the fan *G*. A pipe *P* leads from this auxiliary separator 25 out to the atmosphere. We do not in this application claim the system above described, and will therefore not go into a detailed description of its operation.

So far as we are aware we are the first to 30 separate or grade particles of pulverized material by the use of eddies in a partial vacuum, which vacuum by being regulated will control the relative amount of fine or coarse 35 material passing through the respective openings, through which the graded material passes from the grader.

We are aware that minor changes in the 40 arrangement, construction, and combination of the several parts of our device can be made and substituted for those herein shown and described without in the least departing from the nature and principle of our invention.

Having thus described our invention, what 45 we claim, and desire to secure by Letters Patent, is—

1. In an apparatus of the character described, the combination with a casing having 50 an enlarged head and a tapered lower portion, a substantially tangential inlet-pipe leading into said head, an outlet-pipe leading laterally from said head at a point approximately opposite and in substantially 55 the plane of the inlet-pipe, a discharge-pipe leading from the lower end of the tapered portion, a valve in said pipe, and a suction-fan connected with the outlet-pipe leading from the head; substantially as described.

2. In an apparatus of the character described, the combination with a casing having 60 an enlarged head and a lower tapered portion, a substantially tangential inlet-pipe leading into said head, an outlet-pipe leading laterally from said head, a deflector *E* projecting inwardly from the side and top of 65 the casing for causing the dust-laden air pass-

ing from said inlet to said outlet pipe to take a tortuous passage, an outlet-pipe leading from the lower end of the conical portion of 70 the casing, a valve in said last-mentioned outlet-pipe, and a suction-fan connected with the outlet-pipe leading from the head of the casing; substantially as described.

3. The combination in an apparatus of the 75 character described, of a casing having a polygonal-shaped enlarged head, and a tapering lower portion, an inlet-pipe leading into said head substantially in line with one side thereof, a deflector in the head, joining said 80 side and forming therewith an acute angle directly in the path of the discharge from the inlet-pipe, a discharge from the lower end of the tapering portion, and a suction device for creating a partial vacuum in said head, 85 substantially as described.

4. In an apparatus of the character described, a casing, an inlet-pipe leading into the casing, an outlet from the casing, and a deflector forming with the wall of the casing 90 an acute angle directly in the path of the discharge from the inlet-pipe, substantially as described.

5. In an apparatus of the character described, a casing, a tangentially-arranged inlet-pipe leading into the upper portion of the 95 casing, an outlet from the casing located in substantially the plane of the inlet, a discharge-pipe at the lower portion of the casing, and a deflector forming with the wall of 100 the casing an acute angle directly in the path of the discharge from the inlet-pipe, substantially as described.

6. The combination in an apparatus of the character described, of a casing having an inlet-pipe, a deflector in the casing forming with 105 the wall thereof an acute angle in the path of the discharge from the inlet-pipe, and an outlet from said casing located at a point remote from the inlet and beyond the deflector; substantially as described.

7. The combination in an apparatus of the character described, of a casing having an inlet-pipe, a deflector in the casing forming with 115 the wall thereof an acute angle in the path of the discharge from the inlet-pipe, an outlet from said casing located at a point remote from the inlet and beyond the deflector, and means for creating a partial vacuum in the casing; substantially as described.

8. The combination in an apparatus of the character described, of a casing having an inlet-pipe near its upper end, a deflector in the casing forming with the wall thereof an acute angle in the path of the discharge from the inlet-pipe, an outlet from the casing at the upper portion thereof located at a point remote from the inlet and beyond the deflector, an outlet from the lower portion of the casing, a valve in said last-mentioned outlet, and a suction device associated with said first-mentioned outlet; substantially as described.

9. The combination in an apparatus of the character described, of a casing having an en-

- larged upper portion or head and a tapered lower portion, an inlet-pipe for said casing arranged to discharge into the head or upper portion thereof, a deflector in the casing forming with the wall thereof an acute angle in the path of the discharge from the inlet-pipe, an outlet from the casing at the upper portion thereof located at a point remote from the inlet and beyond the deflector, an outlet from the lower portion of the casing, a valve in said last-mentioned outlet, and a suction device associated with said first-mentioned outlet; substantially as described.
10. The combination in an apparatus of the character described, of a casing having an inlet-pipe at the upper portion thereof, a deflector secured at its end to the casing at one side thereof and projecting laterally thereinto and in the path of the discharge from the inlet-pipe, an outlet from said casing located at a point remote from the inlet and beyond the deflector, an outlet from the lower portion

of the casing, a valve in said last-mentioned outlet, and a suction device associated with said first-mentioned outlet; substantially as described.

11. The combination in an apparatus of the character described, of a casing having an inlet-pipe at the upper portion thereof and an air-outlet, a deflector secured at its end to the casing at one side thereof and projecting laterally thereinto and in the path of the discharge from the inlet-pipe, and an outlet from the lower end of the casing; substantially as described.

In testimony whereof we hereunto affix our signatures, in the presence of two witnesses, this 14th day of December, 1900.

WILLIAM S. OSBORNE.
ELWIN C. BRYANT.
